(57) **CLAIM**

I claim the ornamental design for a fishing lure with antlers, as shown and described.

DESCRIPTION

FIG. 1 is a perspective view of a fishing lure with antlers showing the new design;
FIG. 2 is front view thereof;
FIG. 3 is a rear view thereof;
FIG. 4 is a side view thereof;
FIG. 5 is an opposite side view thereof;
FIG. 6 is a top view thereof;
FIG. 7 is a bottom view thereof;
FIG. 8 is a perspective view showing the design of FIG. 1 in an alternate environment of use;
FIG. 9 is a perspective view showing the design of FIG. 1 in an alternate environment of use; and,
FIG. 10 is a perspective view showing the design of FIG. 1 in an alternate environment of use.

The broken lines in FIGS. 1-10 illustrate environmental structure and form no part of the claimed design.
